Morison S. Cousins, Bayside, N.Y., assignor to
Tensor Corporation, Brooklyn, N.Y.

Filed Feb. 7, 1966, Ser. No. 950

Term of patent 14 years

(Cl. D48—20)

FIG. 1 is a perspective view of a desk lamp, showing my new design;

FIG. 2 is a side elevational view thereof;

FIG. 3 is a front elevational view thereof;

FIG. 4 is a top view thereof; the opposite side of the pivot structure interconnecting the shade and upper end of the lamp arm is a mirror image of the structure shown in FIGS. 1, 4 and 5 and otherwise similar to the arm center pivot design as shown in FIG. 3;

FIG. 5 is a rear elevational view thereof; and

FIG. 6 is a bottom view thereof.

I claim:

The ornamental design for a desk lamp, as shown and described.
